UNITED STATES PATENT OFFICE.

CALVIN K. SCHADE, OF CANTON, OHIO, ASSIGNOR TO THE BERGER MANUFACTURING COMPANY.

LANTERN.

No. 918,476.

Specification of Letters Patent.

Patented April 13, 1909.

Application filed November 5, 1908. Serial No. 461,186.

To all whom it may concern:

Be it known that I, CALVIN K. SCHADE, a citizen of the United States, resident of Canton, county of Stark, and State of Ohio, have invented a new and useful Improvement in Lanterns, of which the following is a specification, the principle of the invention being herein explained and the best mode in which I have contemplated applying that principle, so as to distinguish it from other inventions.

My invention relates to lanterns, its object being to procure a lantern construction which will be simple and efficient in its operation and construction.

The said invention consists of means hereinafter fully described and specifically set forth in the claims.

The annexed drawing and the following description set forth in detail certain mechanism embodying the invention, the disclosed means, however, constituting but one of various forms in which the principle of the invention may be applied.

In said annexed drawing:—Figure 1 is a front elevation of a lantern embodying my invention and showing the parts in their normal positions. Fig. 2 is a view similar to that of Fig. 1, in which the globe-carrying frame is shown in its elevated position. Fig. 3 is a similar elevation showing the detachable portion of the globe-carrying frame disengaged and the hood or canopy raised preparatory to the removal of the globe. Figs. 4, 5 and 6 are detail views.

The main frame A of the lantern is of the usual tubular construction provided at its lower portion with the oil reservoir A' and at its upper portion with the hood or canopy guide A². The usual handle or bail A³ is provided.

The globe-carrying frame comprises a lower globe seat b, two oppositely disposed and laterally extending protecting loops b' b², an arched elastic portion b³ and the hood or canopy B. The said seat is formed of four tubular metallic sections b⁴ b⁵, as shown in Fig. 4. The loop portion b' passes through one of the tubular portions b⁴, is then bent upwardly and laterally, then toward the opposite side, downwardly and then passes through the other tubular portion b⁴ of the seat, the extremity extending laterally to form a projection b⁶. The other loop portion passes through the one tubular

member b⁵ and forms a loop similar to that formed by member b' upon the opposite side of the frame. Its one end projects laterally to form a projection b⁷ and an eye b⁸. This eye engages a guiding upright b⁹ which not 60 only assists in guiding the frame in its upward and downward movement, but also limits the upward movement thereof, as will be readily seen from the drawing.

The arched elastic member b³ is formed at 65 one extremity with a coil b¹⁰ which encircles and forms a seat for the projection b⁸, as shown in the drawings. The extremity of this coil is formed with a downwardly projecting eye b¹¹, Fig. 6. This member b³ extends on upwardly, around member b' to form a loop x and passes through the hood or canopy B, the ventilating apertures in this hood being utilized to permit of such passage. After passing through the hood, the 75 said member then turns downwardly and has its extremity formed with a hook b¹², which engages the other loop member b². The member b³ is so formed as to be in elastic tension when engaging the loop member 80 b² as shown, the form of such member when in the position in which it exerts no elastic tension being that shown in Fig. 3. This feature of said member effects the automatic lifting upwardly of the hood when the 85 hook b¹² is disengaged, thereby permitting the globe C to be removed from the lantern when desired.

Oscillatory mounted upon that tubular frame member adjacent to the member b³, 90 is an actuating lever D, which has a plane of movement substantially parallel with the plane of the main frame, the axis of oscillation of the said lever being, generally speaking, transverse relatively to the axis of the globe. The one end of the lever is formed with a loop d whereby same may be readily grasped, and the opposite end is provided with a hook-like portion d', which engages the eye b¹¹ of the coil b¹⁰, as shown in Figs. 1, 2 and 3. When the globe-carrying frame is at its lowermost position, as shown in Fig. 1, the tension of the lever is such as to permit the loop portion to extend substantially in a vertical direction and the opposite portion thereof to extend downwardly. The length of upward travel of the said frame is made such as to permit the lower end of the lever to assume the position above a plane 105 which is perpendicular to the axis of the 110

globe and which contains the axis of said lever, said plane being indicated by line $y-y$ in Fig. 3, the said lower end normally occupying a position below said plane, as will be observed. The form of the member b^3 is furthermore such that its loop portion, when said member is in its engaged position such as shown in Fig. 1, exerts an outward pressure against the lower portion of the lever 10 arm, when the latter is in its normal position. This tends to maintain such lever in said position. When it is desired to lift the globe-carrying frame upwardly to light or extinguish the lantern, the upper portion of the lever D is turned downwardly so as to reverse the relative positions of its two arms. After the inwardly projecting arm of the lever has passed through the above mentioned plane, that is, has passed the dead 20 center, the elastic tension exerted by the member b^3 throws or tends to throw the now upwardly projecting arm outwardly and maintain the lever in this position. This permits the globe-carrying frame to remain 25 in a raised position such as shown in Fig. 2, without exerting any manual pressure on the lever. In this raising operation, the lifting action is transmitted from the hook portion of the lever to the loop, which latter then 30 engages the fixed projection b^6 , thereby communicating the motion to the said frame.

In this manner a very convenient, economically constructed and simple form of lantern is obtained which is easily and 35 readily manipulated.

What I claim therefore and desire to secure by Letters Patent is:—

1. In a lantern, the combination with a main frame and burner; of a globe-carrying frame mounted upon said main frame so as to be movable toward and from the burner, and including a hood; that portion of the globe-carrying frame which is connected with said hood being normally in elastic 40 tension and disconnectible at one point from the main portion of the globe-carrying frame, whereby said hood may be automatically moved away from said burner when disconnection of said first named portion is 45 effected.

2. In a lantern, the combination with a main frame and burner; of a globe-carrying frame mounted upon said main frame so as to be movable toward and from said burner, and including a hood; that portion of said globe-carrying frame which is connected with said hood being formed with a hook and the main portion thereof being formed with a loop engaged by said hook, said first named 55 portion being normally in elastic tension, whereby the disengagement of said elastic portion will automatically effect a movement of the hood in a direction away from said burner, thereby permitting the globe 60 to be removed.

3. In a lantern, a globe-carrying frame including a portion formed with a globe-seat, and with two oppositely disposed loops; together with a flexible portion extending from one side of the frame, permanently secured to the loop on said side, and engaging the loop on the opposite side thereof. 70

4. In a lantern, a globe-carrying frame including a portion formed with a globe seat and with two oppositely disposed loops; together with a flexible portion extending from one side of the frame secured permanently to the loop on said side, and detachably engaging the loop on the opposite side thereof. 75

5. In a lantern, a globe-carrying frame including a portion formed with a globe seat and with two oppositely disposed loops; together with a flexible portion arched upwardly, permanently secured to one of said loops and extending over from one side to and 80 detachably engaging the loop on the opposite side of said frame; such second portion being in elastic tension when in engagement with said second named loop. 85

6. In a lantern, a globe-carrying frame including a lower portion forming a seat and two oppositely disposed protecting loops; a hood; and an intermediate portion permanently secured to one of said loops and extending from one side of the frame upwardly 90 over to and detachably engaging the loop on the opposite side; said intermediate portion being connected with said hood and being in elastic tension when in engagement with said second named loop. 95

7. In a lantern, the combination of a main frame and burner; a globe-carrying frame mounted thereon so as to be movable toward and from the burner and including a hood; and an operating lever mounted upon 100 said main frame; said globe-carrying frame comprising a lower portion provided with a globe seat and forming a laterally extending loop, and with a portion extending from one side of said globe-carrying frame to the opposite side, detachably engaging said loop, carrying said hood, and being in elastic tension while in engagement with said loop, together with a flexible portion engaging 110 said lever. 115

8. In a lantern, the combination of a main frame and burner; a globe-carrying frame mounted on said main frame movable toward and from said burner; and a lever mounted upon said main frame and having a plane of movement substantially parallel with said main frame; said globe-carrying frame having a flexible portion in engagement with one arm of said lever. 120

9. In a lantern, the combination of a main frame and burner; a globe-carrying frame mounted on said main frame and movable toward and from said burner; and a lever mounted upon said main frame and having its axis of oscillation substantially perpen- 125 130

icular to the plane of said main frame; said globe-carrying frame being provided with an elastic member in engagement with one arm of said lever; the path of movement of said latter frame being such that said arm may assume positions upon opposite sides of a plane substantially perpendicular to the axis of the globe and containing the axis of said lever.

10 10. In a lantern, the combination of a main frame and burner; a globe-carrying frame mounted on said main frame, and movable toward and from the burner, and provided with a fixed lateral projection, together with a flexible portion formed with a loop encircling said projection; a lever

mounted upon said main frame, and having an axis of oscillation transverse relatively to the axis of the globe, and engaging said loop; the path of movement of the latter and said lever being such that they may be caused to assume positions upon opposite sides of a plane perpendicular to the axis of the globe and containing the axis of said lever.
